DESIGN FOR A GAME BOARD

Raymond A. Gould, South Bend, Ind.

Application October 23, 1944, Serial No. 115,927

Term of patent 14 years

(Cl. D34—5)

To all whom it may concern:

Be it known that I, Raymond A. Gould, a citizen of the United States, residing at South Bend, in the county of St. Joseph, State of Indiana, have invented a new, original, and ornamental Design for a Game Board, of which the following is a specification, reference being had to the accompanying drawing, forming part thereof.

Fig. 1 is a plan view of the game board showing my new design.

Fig. 2 is a sectional view of the game board taken on line 2—2 of Fig. 1.

I claim:

The ornamental design for a game board, as shown.

RAYMOND A. GOULD.
